MIXING TUYÈRE

Lucien Chaboisseau, Montreuil-sous-Bois, France,
assignor to Societe de Robinetterie S. A. J.,
Paris, France, a company

Application July 10, 1947, Serial No. 760,174
In France December 29, 1945

Section 1, Public Law 690, August 8, 1946
Patent expires December 29, 1965

3 Claims. (Cl. 103—277)

1

This invention relates to mixing tuyères comprising a movable member, or shutter or flap, for improving the priming of the apparatus and especially although not exclusively to "re-starting" injectors, i. e. automatic priming devices.

In such apparatus, the convergent tuyère, or mixing cone, comprises a shutter which is jointed to the fixed body of the tuyère in such a manner that when the apparatus is starting up its mouth avoids the recompression of the gas in the cone of the tuyère; the said shutter resuming its position as soon as the water sucked in by the opening produced has ensured the condensation of the gas.

According to this invention there is provided an improved mixing tuyère in which the contact surfaces of the tuyère and of its movable shutter are not plane surfaces, as in known injectors, but are cylindrical surfaces.

Because of this improvement, the manufacture of the tuyère and its shutter may be effected as a turning operation while in the known injectors, with plane contact surfaces, the shutter is usually countersunk on the mixing tuyère and is fitted by hand; the manufacturing operation permitted by a construction according to this invention is therefore quicker and simpler as well as allowing of the construction of a number of parts on a lathe at the same time. Moreover, the small wings which are often formed on the shutters to serve as guides are not necessary.

Reference will now be made to the accompanying diagrammatic drawings which illustrate by way of example a preferred embodiment of the invention and in which:

Figure 1 is a plan view of a mixing tuyère constructed in accordance with the invention.

Figure 2 is a sectional elevation.

Figure 3 is a transverse section taken on the line III—III of Figure 2 while

Figure 4 is a transverse section taken on the line IV—IV of Figure 2.

In accordance with this invention, a mixing tuyère comprises a fixed hollow body 1 formed with an inlet 1a for water and gas. The body 1 has a substantially conical part 5 having a portion of the upper perimeter thereof cut away so as to form an opening being arranged substantially in the longitudinal direction of the body 1 and having along the opposite edges thereof longitudinal contact surfaces 4. An open cavity 1b is formed at the other end of the body adjacent to the narrower end of the conical part and communicates with an overflow and a discharge tuyère is screwed into a threaded socket 1c at the

2

same end. A shutter 2 is pivoted about a spindle 3 which is arranged at the edge of the opening in the body 1.

In accordance with the invention, the body 1 of the tuyère and the articulated shutter 2 are arranged with the contact surfaces 4 being shaped as parts of a cylindrical surface having a curvature inclined by an arc of a circle. The shutter 2 and the opening of the conical part are provided with plane transverse surfaces 6 which come into engagement with each other in the closing position of the shutter. The shutter 2 reaches with its forward end as far as the capacity 1b so that it can be easily swung in and out of closing position and the forward end of the shutter 2 need not be accurately made since it does not matter whether the same projects a little bit to the cavity 1b passing through the axis of the nozzle.

I claim:

20. 1. A mixing tuyère comprising in combination, a hollow body having a substantially conical part having a portion of the upper perimeter thereof cut away so as to form an opening being arranged substantially in the longitudinal direction of said body and having along the opposite longitudinal edges thereof contact surfaces; a shutter designed so as to fit said opening in said conical part of said body and having along the opposite longitudinal edges thereof contact surfaces engaging in the closing position of said shutter said contact surfaces of said conical part of said body; and a pivotal connection between said conical part of said body and said shutter, whereby said shutter may be swung in and out of closing position, the contact surfaces of said conical part and of said shutter being shaped as parts of a surface having a curvature defined by an arc of a circle passing through the axis of said body, whereby the contact surfaces of said body and 35 said shutter can be turned simultaneously on a lathe.
2. A mixing tuyère comprising in combination, a hollow body having a substantially conical part having a portion of the upper perimeter thereof cut away so as to form an opening being arranged substantially in the longitudinal direction of said body and having along the opposite longitudinal edges thereof contact surfaces; a shutter designed so as to fit said opening in said conical part of said body and having along the opposite longitudinal edges thereof contact surfaces engaging in the closing position of said shutter said contact surfaces of said conical part of said body; and a pivotal connection between said conical part of said body
- 45

and said shutter, whereby said shutter may be swung in and out of closing position, the contact surfaces of said conical part and of said shutter being shaped as parts of a cylindrical surface having a curvature defined by an arc of a circle passing through the axis of said body, whereby the contact surfaces of said body and said shutter can be turned simultaneously on a lathe.

3. A mixing tuyère comprising in combination, a hollow body having a substantially conical part having a portion of the upper perimeter thereof cut away so as to form an opening being arranged substantially in the longitudinal direction of said body and having along the opposite longitudinal edges thereof contact surfaces; an open cavity formed in said body adjacent to the narrower end of said conical parts; an overflow forming part of said body and communicating with said cavity at the end thereof opposite to said conical parts; a shutter designed so as to fit said opening in said conical part of said body and having along the opposite longitudinal edges thereof contact surfaces engaging in the closing position of said shutter said contact surfaces

of said conical part of said body; and a pivotal connection between said conical part of said body and said shutter, whereby said shutter may be swung in and out of closing position, the contact surfaces of said conical part and of said shutter being shaped as parts of a surface having a curvature defined by an arc of a circle passing through the axis of said body, whereby the contact surfaces of said body and said shutter can be turned simultaneously on a lathe.
